UNITED STATES PATENT OFFICE.

ELMER E. FAIRCHILD, OF ROCHESTER, NEW YORK, ASSIGNOR OF ONE-THIRD TO EDWARD C. GUTLAND AND ONE-THIRD TO HENRY O. ALDERMAN, OF ROCHESTER, NEW YORK.

POST-CARD FRAME OR MOUNT.

No. 849,111.

Specification of Letters Patent.

Patented April 2, 1907.

Application filed November 20, 1906. Serial No. 344,308.

To all whom it may concern:

Be it known that I, ELMER E. FAIRCHILD, a citizen of the United States, residing at Rochester, in the county of Monroe and State 5 of New York, have invented new and useful Improvements in Post-Card Frames or Mounts, of which the following is a specification.

This invention relates to post-card frames or mounts; and the object thereof is to provide a frame or mount for post-cards which will enable the card to be slipped in the frame or mount from the back without distorting the card or the face of the frame or mount, 15 and although the frame or mount is designed particularly for post-cards, yet it is adapted for any purpose for which it may be found desirable.

A further object of the invention is to provide means in a manner, as hereinafter set forth, to constitute a post-card frame or mount which when used will prevent distortion or damage to the card, as well as providing a means for preserving and framing it, and, furthermore, enabling the card when framed or mounted in said means to be suspended or supported from or by the wall of a room or other object.

A further object of the invention is to provide a post-card frame or mount which shall be extremely simple in construction, strong, durable, comparatively inexpensive to manufacture, acting as a means to prevent damage to, and, furthermore, enhancing the appearance of the card when framed or mounted.

With the foregoing and other objects in view the invention consists in the novel construction, combination, and arrangement of parts, which will be hereinafter more specifically described, and illustrated in the accompanying drawings, wherein is shown the preferred embodiment of the invention; but it is to be understood that changes, variations, and modifications can be resorted to 45 which come within the scope of the claims hereunto appended.

In the drawings, Figure 1 is a perspective view of a post-card frame or mount in accordance with this invention. Fig. 2 is a 50 rear view thereof. Fig. 2^a is a sectional view of the post-card frame or mount, showing the card positioned therein. Fig. 3 is a view of the blank from which the frame-section is

formed; and Fig. 4 is a like view of the blank from which the back-section is formed.

A post-card frame or mount in accordance with this invention comprises two sections, one of which is termed the "frame-section" and the other the "back-section." The frame-section is set up from a blank formed 60 of a body portion 1, having a rectangular opening 2, and a pair of side and end flaps 3 4 and 5 6, respectively. Each of the side flaps 3 4 is scored on the rear face thereof, as at 7 8, and on the front face, as at 9, and 65 by such an arrangement folds 10, 11, and 12 are provided, the folds 10 being the inner folds, the folds 11 the intermediate folds, and the folds 12 the outer folds. The end edges of each of the folds 10 are straight, while the 70 end edges of each of the folds 11 and 12 are beveled. The end flaps 5 6 are scored in the same manner as the flaps 3 4, and the end edges of the flaps 5 6 are constructed in a similar manner as the edges of the flaps 3 4.

The same reference characters are applied to the scores and folds of the flaps 5 6 as applied to the scores of the folds of the flaps 3 4.

Preferably the end flaps are of less length than the side flaps, and the side flaps are adapted to be folded over and secured to the front face of the body portion 1 of the blank, so that the longitudinal edges of the said flaps, as well as the end flaps, will be flush with the edges of the opening 2. When the 85 side and end flaps are folded over and upon the body portion 1 of the blank, the end edges of the side flaps are adapted to abut against the end edges of the end flaps and with the folds 10 of all the flaps extending 90 vertically, the folds 11 toward the body portion of the blank at an inclination, and the folds 12 lying flat upon the outer face of the body portion 1 of the blank. The folds 12 have their inner face thereof secured to the 95 outer face of the body portion of the blank, so as to give to the frame-section a bevel extending entirely around the outer face thereof when the side and end flaps are secured in position. This will be evident owing to the 100 inclination of the folds 11 downwardly from the upper terminal of the folds 10. If desired, the frame-section can then be covered with paper, as at 13, to imitate wood, or any other suitable covering may be employed.

The back-section is formed from a rectan-

gular blank 14, of suitable material, and which has the marginal portions of one face thereof secured to the back of the body portion 1 of the blank of the frame-section, and the said blank 14, near the top thereof, is formed with a transversely-extending elongated slot 15 to permit of inserting the post-card 15^a in position in the frame or mount. One of the longitudinal sides of the blank 14 is formed with a pair of slits 16, so as to constitute a tongue 17, the latter being apertured, as at 18. The tongue 17 is not secured to the frame-section, but swings free therefrom, so as to permit of a suitable suspension means extending through the aperture 17 to enable the frame to be hung or supported. The blank 14 is furthermore provided at one end with a pair of slits 19, so as to constitute a tongue 20, which is apertured, as at 21. The tongue 20 performs a like function with the tongue 17. By providing the pair of tongues it is evident that the frame can be hung from one side or from one end. The position of the slot 15 in the blank 14 is such that it will be arranged below one end wall of the opening 2, so that the post-card can be inserted in a convenient manner. The marginal portions of the blank 14 are so secured to the rear face of the body portion 1 of the frame-section so that the post-card can be conveniently slid between the front face of the blank 14 and the rear face of the frame-section when framing or mounting a card.

What I claim is—

35 1. A frame or mount comprising a frame-

section consisting of a body portion provided with an opening and a pair of end and side flaps, each having their inner and outer faces scored to form folds, with the outer folds secured to the outer face of the body portion 40 and flush with said opening, and a back-section having the marginal portions of one face thereof secured to the rear face of the body portion, said back-section provided with a transversely - extending slot near one end 45 thereof.

2. A frame or mount comprising a frame-section consisting of a body portion provided with an opening and a pair of end and side flaps, each having their inner and outer faces 50 scored to form folds, with the outer folds secured to the outer face of the body portion, the inner folds projecting at right angles to the body portion and the intermediate folds extending downwardly at an inclination 55 from the inner to the outer folds, and a back section having marginal portions in one face thereof secured to the rear face of the body portions, said back-section of greater width and length than said opening and having an 60 elongated slot to permit of the insertion of the post-card.

In testimony whereof I have hereunto set my hand in presence of two subscribing witnesses.

ELMER E. FAIRCHILD.
